UNITED STATES PATENT OFFICE

2,043,917

EVAPORATOR FOR REFRIGERATING MACHINES

Leonard W. Atchison, Schenectady, N. Y., assignor to General Electric Company, a corporation of New York

Application November 1, 1934, Serial No. 750,977

20 Claims. (Cl. 62—126)

My invention relates to flooded type evaporators for refrigerating machines.

Flooded evaporators are ordinarily provided with a header or other vapor separating chamber 5 and an extended liquid refrigerant circulatory passage, liquid vaporizable refrigerant being supplied to the evaporator from a compressor-condenser unit, or other refrigerant liquefying apparatus. The liquid refrigerant supplied to the 10 evaporator is preferably injected into the circulatory passage in order to set up a positive flow of refrigerant in a predetermined direction and to increase the velocity of circulation. The 15 circulating liquid refrigerant is vaporized by the absorption of heat from articles contained in the compartment in which the evaporator is located. The passage communicates with the header in with the refrigerant, vaporized by the absorption of heat is separated from the remaining liquid refrigerant, the vaporized refrigerant being 20 returned to the refrigerant liquefying apparatus from the header.

It is an object of my invention to provide an improved arrangement for injecting liquid refrigerant in a flooded evaporator in such manner as 25 to obtain rapid circulation of liquid refrigerant through the passages of the evaporator and thereby obtain the maximum absorption of heat by the liquid refrigerant from the walls of the evaporator.

Further objects and advantages of my invention will become apparent as the following description proceeds and the features of novelty which characterize my invention will be pointed 30 out with particularity in the claims annexed to and forming a part of this specification.

For a better understanding of my invention, reference may be had to the accompanying drawing in which Fig. 1 is a front elevation of a 35 refrigerating machine having an evaporator embodying my invention; Fig. 2 is a perspective view partly in section of the evaporator shown in Fig. 1; Fig. 3 is a sectional view on the line 3—3 of the evaporator shown in Fig. 2, and Fig. 4 is a fragmentary view, partly in section, of a 40 modified form of equalizer conduit for the evaporator shown in Fig. 2.

Referring to the drawing, in Fig. 1, I have 45 shown a refrigerating machine including an evaporator embodying my invention. In this machine, a motor and compressor are arranged in an hermetically sealed casing 10. Gaseous refrigerant is compressed by the motor driven compressor in the casing 10 and is discharged into a condenser 11 where it is liquefied. The liquefied

refrigerant flows from the condenser 11 through a flow controlling float valve 12 into a liquid line 13 from which the liquid refrigerant is injected into an evaporator 14. The liquid refrigerant is vaporized in the evaporator by the absorption of heat and the vaporized refrigerant is returned to the compressor through the suction line 14a.

The evaporator 14 comprises two complementary sheet metal portions 15 and 16. The inner smooth sheet 16 is provided with a pair of transverse indentations 17 and 18 adjacent the upper edges thereof, which cooperate with the complementary indentations 19 and 20 in the outer sheet 15 to form the cylindrical headers 21 and 22. The outer sheet 15 is also provided with a plurality of parallel indentations or corrugations 23 to 31, inclusive, which cooperate with the smooth sheet 16 to form depending refrigerant circulatory passages connecting the headers 21 and 22 and communicating with the headers below the normal liquid levels therein. The inner smooth sheet 16 is made slightly larger than the outer sheet 15 and its longitudinal edges are folded over the adjacent edges of the sheet 15. The sheets 15 and 16 are then welded or otherwise secured 25 together along their peripheral edges and between the refrigerant passages formed therein. The welding may be in the form of a line weld or a series of spot welds, or the sheets may be brazed together or joined in some other manner, if desired. After having been secured together 30 the sheets 15 and 16 are bent into a U-shape, as shown in the drawing. Inturned flanges 32 and 33 are provided at the top of the legs of the U to facilitate the mounting of the evaporator 35 14 in the cabinet 34 by screws or bolts passing through the holes 35 and 36 in the flanges 32 and 33 respectively. Articles to be frozen, such as 40 trays of water, may conveniently be supported on the intermediate part of the sheet metal portions and within the compartment, thus formed by the evaporator 14.

Liquid vaporizable refrigerant is supplied to the evaporator 14 through the liquid line 13 which enters the evaporator through the side wall of the header 22, passes downwardly through the refrigerant passage 31 and terminates in a transverse flute 31 formed in the inner sheet 16. Liquid refrigerant is injected upwardly into the refrigerant circulatory passages from the refrigerant supply conduit 13. This arrangement for injecting liquid refrigerant into a plurality of refrigerant circulatory passage communicating with a header of an evaporator is not my invention, but is the invention of Christian Steenstrup 55

and is described and claimed in his copending application, Serial No. 658,321, filed February 24, 1933, and assigned to General Electric Company, the assignee of my present invention.

- 5 In accordance with my invention, the evaporator is provided with passages for recirculating liquid refrigerant from one header to the other in order that all of the liquid refrigerant may be most efficiently utilized for absorbing heat 10 from articles to be cooled. I prefer to inject the liquid refrigerant into a centrally located group of refrigerant passages, the recirculating passages being located on each side thereof, as shown in the illustrative form of my invention, in order 15 that the length of the circulatory path of the liquid refrigerant through the headers may be reduced to a minimum. In the form of my invention, which is illustrated in the drawing, liquid refrigerant is injected through the refrigerant circulatory passages 25, 26, 27, 28, and 29, from the holes 38 in the upper side of the refrigerant supply conduit 13, as indicated by the arrows in Fig. 2. The liquid refrigerant thus injected passes upwardly into the header 22, and as it circulates 20 through these passages 25 to 29 inclusive, it absorbs heat from articles contained in the cabinet 34 in which the evaporator is located and is partially vaporized by such absorption of heat. The vaporized refrigerant separates from the liquid refrigerant in the header 22 and the liquid refrigerant is recirculated through the refrigerant circulatory passages 23, 24, 30, and 31. The liquid refrigerant from the header 22 passes 25 downwardly through these passages as indicated by the arrows in Fig. 2 and enters the header 21. The liquid refrigerant, passing through the passages 23, 24, 30, and 31 is also partially vaporized by the absorption of heat and the vaporized refrigerant is collected in the header 21. The liquid refrigerant, remaining in the header 21, flows 30 downwardly through the passages 25 to 29, inclusive, back to the injection point where it is entrained by fresh liquid refrigerant entering the evaporator from the liquid supply conduit 13. The headers 21 and 22 are normally maintained 35 about half full of liquid refrigerant, the vaporized refrigerant being collected in the upper parts of the headers. The vaporized refrigerant collected in the header 22 passes through an equalizing conduit 39 to the header 21. In the evaporator shown in Fig. 2, the equalizing conduit 39 is connected to the headers 21 and 22 above the normal liquid levels therein and serves simply as a 40 pressure equalizer and to convey the vaporized refrigerant.

I have found that when a refrigerant, such as methyl formate is used as a refrigerant, in an evaporator of the type described, in which the difference in density between the lubricating oil and the refrigerant is small and in which the lubricating oil is broken up into small globules by the agitation caused by the injectors, the oil will circulate almost as a part of the refrigerant body until it reaches a sufficiently quiet place to permit separation therefrom by gravity. Thus it will be seen that the evaporator shown in Fig. 2 is particularly adapted for use with refrigerants of this type, as it is not necessary that the equalizing conduit 39 serve to convey oil from the header 22 to the header 21 since it will be carried thereto by the liquid refrigerant.

A suction line 14a is connected to the header 21 rather than to the header 22 as the liquid refrigerant in the header 21 is agitated to a lesser extent than that in the header 22, since the injectors

are more remote therefrom, and it is desirable to locate the suction line connection in a quiet zone in order to guard against the return of liquid refrigerant to the compressor and also to facilitate the separation of oil from the refrigerant by gravity. In order to further guard against the entrance of liquid refrigerant into the suction line 14a, and also to provide a quiet zone for the collection of lubricant on the surface of the liquid refrigerant, I have provided a baffle arrangement 10 in the header 21 as best shown in Fig. 2. This arrangement includes a pair of disc shaped baffles 41 and 42 connected by a cross piece 43. The lower portions of the baffles 41 and 42 are cut away and holes or apertures 44 and 45 are provided in them respectively to permit a limited flow of refrigerant past the same. The liquid refrigerant in the passages 26, 27 and 28 which are between the baffles 41 and 42 is flowing downwardly out from the header 21; this arrangement serves further to insure a quiet zone of liquid in the vicinity of the suction line. An oil separation cup 46 is supported about the end of the suction line 14a by downstruck portions 47 and 48 of cross piece 43. Holes 49 are provided in the sides of cup 46 in order that oil may be skimmed off the surface of the liquid refrigerant in the header 21 and returned to the compressor in casing 10 through the suction line 14a, these holes being placed high enough on the sides of the cup 46 to preclude the entrance therethrough of liquid refrigerant.

In Fig. 4, I have shown a modified form of equalizing tube and header arrangement which is more particularly adapted for use with refrigerants, such as sulphur dioxide, which have a density which differs materially from that of the lubricating oil used therewith. As shown in Fig. 4, the headers 21a and 22a are connected by an equalizing conduit 50 communicating with these headers at the normal liquid levels therein so that both liquid and vaporized refrigerant may be circulated from the header 22a to the header 21a, through this equalizing conduit 50. In that way oil, which may collect on the surface of the liquid refrigerant in the header 22, is carried to the header 21 by the liquid refrigerant circulating through the equalizing conduit 50 and may be returned to the compressor in the casing 10 through the suction line 14a.

While I have shown a particular embodiment of my invention in connection with a compression refrigerating machine, I do not desire my invention to be limited to the particular construction shown and described, and I intend in the appended claims to cover all modifications within the spirit and scope of my invention.

What I claim as new and desire to secure by Letters Patent of the United States, is:

1. A flooded evaporator for refrigerating machines including a pair of headers, means depending below said headers and having a refrigerant circulatory passage formed therein for conveying refrigerant between said headers, means injecting liquid refrigerant into said passage for producing circulation of liquid refrigerant from one of said headers to the other header, said means having a second refrigerant circulatory passage formed therein and communicating with said headers below the normal liquid levels therein for providing a path for the recirculation of liquid refrigerant from said other header to said one header.

2. A flooded evaporator for refrigerating machines, comprising complementary sheet metal portions at least one of said sheet metal portions

- having an indentation therein forming a header, a plurality of refrigerant circulatory passages formed between said sheet metal portions and communicating with said header below the normal liquid level therein, said passages communicating with each other remote from said header, and means for injecting liquid refrigerant into only part of the total number of said refrigerant passages and remote from said header, the remainder of said refrigerant passages providing a path for the recirculation of liquid refrigerant from said header.
3. A flooded evaporator for refrigerating machines comprising a pair of headers, means extending between said headers providing a horizontal surface for supporting articles to be cooled, said means including a plurality of refrigerant circulatory passages communicating with said headers below the normal liquid levels therein, and means injecting liquid refrigerant into only a part of the total number of said passages in portions thereof remote from said headers for producing circulation of liquid refrigerant from one of said headers to the other of said headers, the remainder of said refrigerant passages providing a path for the recirculation of liquid refrigerant from said other header to said one header.
4. An evaporator of the flooded type for refrigerating machines comprising complementary sheet metal portions, at least one of said sheet metal portions having indentations therein forming headers adjacent the opposite edges of said sheet metal portions, the intermediate part of said sheet metal portions providing a support for articles to be cooled, a plurality of refrigerant circulatory passages formed between said sheet metal portions and communicating with said headers below the normal liquid levels, therein, and means injecting liquid refrigerant into only a part of the total number of said passages in portions thereof remote from said headers for producing circulation of liquid refrigerant from one of said headers to the other of said headers, the remainder of said refrigerant passages providing a path for the recirculation of liquid refrigerant from said other header to said one header.
5. A flooded evaporator for refrigerating machines comprising complementary U-shaped sheet metal portions, at least one of said sheet metal portions having indentations therein forming a header adjacent the top of each leg of the U and a plurality of depending refrigerant circulatory passages communicating with said headers below the normal liquid levels therein, and means injecting liquid refrigerant into only a part of the total number of said passages remote from said headers for producing circulation of liquid refrigerant from one of said headers to the other of said headers, the remainder of said refrigerant passages providing a path for the recirculation of liquid refrigerant from said other header to said one header.
6. A flooded evaporator for refrigerating machines comprising complementary U-shaped sheet metal portions, at least one of said sheet metal portions having indentations therein forming a header adjacent the top of each leg of the U and a plurality of depending refrigerant circulatory passages communicating with said headers below the normal liquid levels therein, a transverse flute in one of said sheet metal portions, and means injecting liquid refrigerant into only a part of the total number of said passages remote from said headers including a refrigerant conduit located in said transverse flute, the remainder of said re-
- frigerant passages providing a path for the recirculation of liquid refrigerant from one of said headers to the other.
7. A flooded evaporator for refrigerating machines including a header, means for circulating liquid refrigerant supplied to said evaporator, said means including a plurality of refrigerant circulatory passages communicating with said header below the normal liquid level therein and communicating with each other at a point remote from said header, and means for injecting liquid refrigerant into a central group of said refrigerant passages remote from said header, the remainder of said refrigerant passages providing a path for the recirculation of liquid refrigerant from said header.
8. A flooded evaporator for refrigerating machines including a pair of headers, means for circulating liquid refrigerant supplied to said evaporator, said means including a plurality of depending refrigerant circulatory passages opening into said headers below the normal liquid levels therein and means for injecting liquid refrigerant into a centrally located group of said passages at points remote from said headers, the remainder of said passages providing a path for the recirculation of liquid refrigerant from one of said headers to the other.
9. A flooded evaporator for refrigerating machines including a pair of headers, means for circulating liquid refrigerant supplied to said evaporator, said means including a plurality of refrigerant circulatory passages communicating with said headers below the normal liquid levels therein, means for injecting liquid refrigerant into a part of said passages at points below one of said headers, the remainder of said passages providing a path for the recirculation of liquid refrigerant from one of said headers to the other, and means for removing vaporized refrigerant from the one of said headers most remote from said first mentioned means.
10. A flooded evaporator for refrigerating machines including a pair of headers, means for circulating liquid refrigerant supplied to said evaporator, said means including a plurality of refrigerant circulatory passages communicating with said headers below the normal liquid levels therein, means for injecting liquid refrigerant into a centrally located group of said passages at points below one of said headers, the remainder of said passages providing a path for the recirculation of liquid refrigerant from one of said headers to the other, and means for removing vaporized refrigerant from the one of said headers most remote from said first mentioned means.
11. A flooded evaporator for refrigerating machines comprising complementary U-shaped sheet metal portions, at least one of said sheet metal portions having indentations therein forming a header adjacent to the top of each leg of the U, a plurality of depending refrigerant circulatory passages formed between said sheet metal portions and communicating with said headers below the normal liquid level therein, means for injecting liquid refrigerant upwardly into part of said passages at a point below one of said headers, the remainder of said passages providing a path for the recirculation of liquid refrigerant from said one header to the other of said headers, and means for removing vaporized refrigerant from said other header.
12. A flooded evaporator for refrigerating machines comprising complementary U-shaped sheet metal portions, at least one of said sheet metal

- portions having indentations therein forming a header adjacent the top of each leg of the U, a plurality of depending refrigerant circulatory passages formed between said sheet metal portions and communicating with said headers below the normal liquid level therein, a transverse flute in one wall of said U-shaped evaporator, means for injecting liquid refrigerant into a part of said passages including a refrigerant conduit located in said transverse flute, the remainder of said passages providing a path for the recirculation of liquid refrigerant from the header above said transverse flute to the other of said headers, and means for removing vaporized refrigerant from said other header.
13. A flooded evaporator for refrigerating machines comprising complementary U-shaped sheet metal portions, at least one of said sheet metal portions having indentations therein forming a header adjacent the top of each leg of the U, a plurality of depending refrigerant circulatory passages formed between said sheet metal portions and communicating with said headers below the normal liquid level therein, a transverse flute on one wall of said U-shaped evaporator, means for injecting liquid refrigerant upwardly in a centrally located group of said passages and into one of said headers, the remainder of said passages providing a path for the recirculation of liquid refrigerant from said one header to the other of said headers, and means for removing vaporized refrigerant from said other header.
14. A flooded evaporator for refrigerating machines comprising complementary U-shaped sheet metal portions, at least one of said sheet metal portions having indentations therein forming a header adjacent the top of each leg of the U, a plurality of depending refrigerant circulatory passages formed between said sheet metal portions and communicating with said headers below the normal liquid levels therein, and means for injecting liquid refrigerant into a part of said passages including a refrigerant conduit entering the wall of one of said headers passing downwardly through one of said refrigerant passages to a point remote from said last mentioned header, the remainder of said refrigerant passages providing a path for the recirculation of liquid refrigerant from one of said headers to the other.
15. A flooded evaporator for refrigerating machines comprising complementary U-shaped sheet metal portions, at least one of said sheet metal portions having indentations therein forming a header adjacent the top of each leg of the U, a plurality of depending refrigerant circulatory passages formed between said sheet metal portions and communicating with said headers below the normal liquid levels therein, a transverse flute on one wall of said U-shaped evaporator, means for injecting liquid refrigerant upwardly into a centrally located group of said passages including a refrigerant conduit entering said evaporator through a wall of the header above said transverse flute passing downwardly through one of said refrigerant passages and through said transverse flute, the remainder of said refrigerant passages providing a path for the recirculation of liquid refrigerant from the header above said transverse flute to the other of said headers.
16. A flooded evaporator for refrigerating machines comprising complementary U-shaped sheet metal portions, at least one of said sheet metal portions having indentations therein forming a header adjacent the top of each leg of the U, a plurality of depending refrigerant circulatory pas-
- sages formed between said sheet metal portions and communicating with said headers below the normal liquid levels therein, a transverse flute on one wall of said U-shaped evaporator, means for injecting liquid refrigerant upwardly into a centrally located group of said passages including a refrigerant conduit entering said evaporator through a wall of the header above said transverse flute passing downwardly through one of said refrigerant passages and through said transverse flute, the remainder of said refrigerant passages providing a path for the recirculation of liquid refrigerant from the header above said transverse flute to the other of said headers, and means for removing vaporized refrigerant from said other header.
17. A flooded evaporator for refrigerating machines including a pair of headers, means for circulating liquid refrigerant supplied to said evaporator, said means including a plurality of depending refrigerant circulatory passages communicating with said headers below the normal liquid levels therein, a pressure equalizer tube connecting said headers above the normal liquid levels therein, and means for injecting liquid refrigerant into a part of said passages remote from said headers, the remainder of said passages providing a path for the recirculation of liquid refrigerant from one of said headers to the other.
18. A flooded evaporator for refrigerating machines including a header, means for circulating liquid refrigerant supplied to said evaporator, said means including a refrigerant circulatory passage communicating with said header, a suction line extending within said header for the removal of vaporized refrigerant therefrom, a cup surrounding the end of said suction line within said header, said cup being provided with an aperture in the side thereof to provide for the admission of lubricant to said cup from the surface of liquid refrigerant in said header, and means arranged in said header and obstructing the flow of liquid refrigerant in said header past said cup for providing a quiet zone about said cup in order that said lubricant may accumulate on the surface of said liquid refrigerant in said header.
19. A flooded evaporator for refrigerating machines including a header, means for circulating liquid refrigerant supplied to said evaporator, said means including a refrigerant circulatory passage communicating with said header, a suction line extending within said header for the removal of vaporized refrigerant therefrom, a cup surrounding the end of said suction line within said header, said cup being provided with an aperture in the side thereof to provide for the admission of lubricant to said cup from the surface of liquid refrigerant in said header, and means arranged in said header and obstructing the flow of liquid refrigerant in said header past said cup for providing a quiet zone about said cup in order that said lubricant may accumulate on the surface of said liquid refrigerant in said header, said means including apertured discs supported in said header on each side of said cup in spaced relation thereto.
20. A flooded evaporator for refrigerating machines including a header, means for circulating liquid refrigerant supplied to said evaporator, said means including a plurality of refrigerant circulatory passages communicating with said header below the normal liquid level therein and communicating with each other at a point remote from said header, means injecting liquid refrigerant into a plurality of said passages for circulating liquid refrigerant away from said header

through a group of said passages and for returning said liquid refrigerant to said header through the remainder of said passages, means including a pair of baffles spaced apart and arranged within said header for providing a quiet zone of liquid within said header, the refrigerant circulatory passages entering said header between

said baffles being in said group circulating refrigerant away from said header, and a suction line extending within said header between said baffles for the removal of vaporized refrigerant from said evaporator.
